DESIGN FOR A CALENDAR STAND

Carlyle N. Montanye, Baltimore, Md.

Application March 20, 1934, Serial No. 51,111

Term of patent 7 years

To all whom it may concern:

Be it known that I, CARLYLE N. MONTANYE, a citizen of the United States, residing at Baltimore, in the State of Maryland, have invented a new, original, and ornamental Design for Calendar Stands, of which the following is a specification, reference being had to the accompanying drawing, forming part thereof.

Fig. 1 is a front elevation of a calendar stand, showing my new design.

Fig. 2 is a top plan view thereof.

I claim:

The ornamental design for a calendar stand, as shown.

CARLYLE N. MONTANYE.
